GATE

Lyle C. Tilbury, Hunt, Tex.

Application February 15, 1947, Serial No. 728,835

9 Claims. (Cl. 39—22)

1
This invention relates to a gate.

An object of the invention is to provide a gate for roadways which will be normally maintained in closed position but which may be readily opened by a motor vehicle to permit passage of the vehicle and will be temporarily latched in opened position so that it will not be liable to strike the vehicle in closing, with means for automatically releasing the latch to allow the gate to swing to closed position.

In addition to the novel means for latching the gate open the invention also includes as an improvement a novel type of trolley hereinabove referred to for releasing the latching means to allow the gate to swing to closed position when opened.

Other objects and advantages will be apparent from the following specification which is illustrated by the accompanying drawings, wherein:

Figure 1 is a side view of the gate shown in closed position and partly in section.

Figure 2 is a top, plan view of the gate shown in closed position showing the latching mechanism partly broken away.

Figure 3 is a side elevation of the gate shown in open position and partly in section.

Figure 4 is an enlarged, fragmentary, sectional view taken on the line 4—4 of Figure 3.

Figure 5 is a fragmentary, sectional view taken on the line 5—5 of Figure 1.

Figure 6 is a fragmentary, vertical, sectional view taken on the line 6—6 of Figure 1.

Figure 7 is a rear elevation of the gate latching mechanism showing the roller in final latched position, and

Figure 8 is a rear elevational view of the gate latching mechanism showing the gate roller approaching latched position.

Referring now more particularly to the drawings wherein like numerals of reference designate the same parts in each of the figures, the numerals 1 and 2 designate the top and bottom bars, respectively, of the gate.

In the present illustration these bars are secured at their rear ends to the upper and lower ends, respectively, of the rear bar 3. The lower end of the bar 3 is extended beneath the bottom bar 2 and is formed into a tapering spindle 4.

The forward ends of the top and bottom bars 1 and 2 are secured to the front bar 5 of the gate.

The parts hereinabove described are preferably formed of metal and may be welded or otherwise secured together.

The gate is hinged to an upstanding post 6 in

2
the following manner: a ratchet plate 7 is welded, or otherwise secured to the post 6 near the lower end thereof and is provided with a central socket 8 in which the spindle 4 is seated. There is a U-bolt 9 whose shanks are externally threaded and extended through the top of the post 6 and are clamped thereto by clamp nuts 10, 10 which are threaded onto the shank of the U-bolt 9, as shown in Figures 1 and 2. Welded, or otherwise secured, to the top bar 1 near its rear end there is a tubular anchor 11 and fitted through this anchor there is the outwardly threaded shank of the eye bolt 12 which is clamped in position by clamp nuts 13, 13. The eye of the bolt 12 is elongated, as best shown in Figure 2, and the U-bolt 9 is linked through it. This elongated eye allows the forward end of the gate to have a limited range of vertical movement.

Welded, or otherwise secured, to the rear bar 3 and to the bottom bar 2 there is a forwardly extended plate 14 which also forms a brace for the gate and swinging from this plate, with its upper end pivoted thereto, there is a swinging latch 15 whose lower end extends beneath said plate.

25 The operative margin of the ratchet plate 7 is formed with the ratchet teeth 16, the teeth on each side of this plate being pitched in opposite directions, or rearwardly, and the forward margin of the ratchet plate 7 between the series of oppositely pitched teeth 16 is formed with an arcuate notch 17.

Secured to the underside of the ratchet plate 7, beneath the notch 17 and extending forwardly beyond said plate there is a guide member 18 whose outer end is upturned and its inner side formed with a convex bearing face 19 which has the same curvature as the notch 17 and is spaced therefrom to form a guide.

Also pivoted to the plate 14 and in alignment behind the latch 15 there is a latch releasing lever 20 whose lower end is formed with a forwardly extended striker 21 arranged to strike the latch 15 when the lever 20 is actuated.

There is a ball track 22 near the top of the gate whose ends are secured to the rear end front bars 3 and 5, respectively.

As is clearly illustrated in Figure 4, this ball track is preferably in the form of an inverted channel with the margins of its side flanges turned inwardly and upwardly so that the spherical weight 23 therein may rest upon said upwardly turned margins and move there along with a minimum of friction.

The upper end of the lever 20 projects up into 55 said channel between said inwardly turned mar-

gins, as is clearly indicated in Figures 1, 3 and 6. As will be noted from an inspection of Figure 1, the track is mounted on the gate so that it will decline slightly forwardly when the gate is closed but when the gate is open, as shown in Figure 3, on account of the hinge connection between the gate and the post 6, as above described, the free end of the gate will be elevated and the track 22 will decline rearwardly, or toward the post 6.

Out beyond the free, or forward, end of the gate, there is the upstanding post 24 which is provided with a rearwardly extended stop 25 and beneath said stop there is a latch plate 26 having an upwardly flared notch 27 providing with the guide faces 28, 28 on each side of said notch and said latch plate 26 is provided with the downwardly diverging guideways 29, 29.

The forward end of the bottom bar 2 of the gate is extended beyond the front bar 5 and is formed into a spindle 30 on which the roller 31 is retained by means of a suitable retainer, such as a cotter key 32.

When the gate is in normal, or closed, position the roller 31 will rest in the notch 27 beneath the stop 25, as shown in Figure 7. The gate is equipped with a suitable push plate, or bumper plate, as 33, one on each side and upon lateral pressure being exerted against the gate the roller 31 will ride up along the opposing faces 28 and out of the notch 27 and the gate may be swung open. On the other hand as the gate swings toward closed position the roller 31 will ride up along the corresponding guideway 29 correspondingly elevating the forward, or free, end of the gate.

This is permitted by reason of the oblong eye of the U-bolt 12. In order to prevent the movement of the gate from carrying the roller 31 across the notch 27 the stop 25 has been positioned so that the roller 31 will come into contact with it, as shown in Figure 8, and the closing movement of the gate will be stopped and the roller 31 will drop down into, and be retained in, the notch 27, as indicated in Figure 7.

When a motor vehicle approaches the gate its front bumper will come into contact with the opposing bumper plate 33 and the gate will be forced open. As the gate moves toward open position the swinging latch 15 will ride past the teeth 16. Centrifugal force will hold the spherical weight 23 at the outer end of the track 22 as the gate swings open and when the gate has reached the limit of its movement toward open position the latch 15 will engage behind the corresponding tooth 16 and prevent the gate from swinging back to closed position and possibly striking against the vehicle before the latter has cleared the gate; however, the weight 23 will thereupon move along the track 22 which, with the gate opened, will decline rearwardly and said weight will strike the upper end of the releasing lever 20 forcing said upper end rearwardly and forcing the lower end thereof forwardly and causing the striker 21 to come into contact with, and release, the swinging latch 15 whereupon the gate will be free to swing on to closed position. As the gate moves toward closed position the striker 21 will remain in contact with said latch and will hold it outwardly so that it will not again engage with one of the teeth 16 to stop the closing movement of the gate. As the gate approaches its final closed position the lower end of the latch 15 will come into contact with the convex bearing face 19 and said latch will be

moved radially inwardly relative to the plate 1 and will force the lower end of the releasing lever 20 in the corresponding direction and when said releasing lever passes center it will remain in said last indicated position, as shown in Figure 1, until again actuated and the latch 15 will finally come to rest in the notch 17 as indicated in Figure 5. The weight 23, upon movement of the gate to closed position will move outwardly toward the free end of the gate to the position indicated in dotted lines in Figure 1. The range of movement of the lever 20 is limited by the contact of a cross-pin 34, through its upper end, with the inwardly turned margins of track 22.

It is obvious that the gate may be swung in either direction to open position so that it may be opened by a vehicle traveling in either direction.

The drawings and description are illustrative merely while the broad principle of the invention will be defined by the appended claims.

What I claim is:

1. The combination with a gate post, of a gate hinged to the post to swing about an upright axis into open or closed position, a ratchet plate fixed relative to the post adjacent its lower end on which the gate is mounted to pivot, said plate having marginal ratchet teeth, a latch on the gate arranged to engage a tooth of the plate when the gate is in open position to latch the gate open, latch releasing means including a releasing element movably supported on the gate in cooperative engagement with said latch and impact means on the gate movable by gravity upon opening of the gate into contact with said releasing element to automatically release the latch to allow the gate to swing to closed position.

2. The combination with a gate post, of a gate, means for hinging the gate to the upper end of the post, a ratchet plate fixed relative to the lower end of the post, means pivotally connecting the gate to the ratchet plate, a latch pivoted to the gate and engageable with said ratchet plate when the gate is in open position to latch the gate open, a latch releasing element on the gate, and an impact body movable along the gate, when the gate is in open position to actuate said releasing element to effect release of the latch to allow the gate to swing to closed position.

3. The combination with a gate post, of a ratchet plate fixed in position relative to the lower end of the post, a gate one end of which is pivotally mounted on said plate, means for connecting said end of the gate to the upper end of the post whereby the gate may swing about an upright axis to open or closed position, means on the gate and plate, respectively, arranged to interlock to temporarily hold the gate in open position, said means including a latch, a release element on the gate normally in inactive position and an impact element on the gate movable by gravity, when the gate is open, into contact with said element to actuate the same into contact with the latch to release said interlocking means to allow the gate to swing to closed position.

4. The combination with a gate post, of a ratchet plate fixed in position relative to the lower end of the post, a gate one end of which is pivotally mounted on said plate, means for connecting said end of the gate to the upper end of the post whereby the gate may swing about an upright axis to open or closed position, means on the gate and plate, respectively, arranged to interlock to temporarily hold the gate in open position, said means including a latch, a release

element movably supported on the gate in co-operative engagement with the latch and on the gate normally in inactive position and an impact element on the gate movable by gravity, when the gate is open, into contact with said element to actuate the same into contact with the latch to release said interlocking means to allow the gate to swing to closed position, and means arranged to be contacted by the latch and adapted to actuate the latch, as the gate approaches closed position, to move said releasing element to its original inactive position.

5. The combination with a gate post of a gate supporting element fixed relative to the lower end of the post, a gate pivotally supported on said element and having a hinged connection with the upper end of the post whereby the gate may swing about an upright axis into open or closed position, a track on the gate, an impact body movable along the track, interlocking means carried by said supporting element and the gate and including a latch engageable with the supporting element, when the gate is open, to latch the gate in open position, a releasing element pivotally mounted on the gate one end of which is associated with the track and whose other end is in alignment with the latch, said releasing element being normally inactive and being arranged to be actuated by said impact element, when the gate is open, to move the impact element into contact with the latch to release the same to permit the gate to close.

6. The combination with a gate post of a gate supporting element fixed relative to the lower end of the post, a gate pivotally supported on said element and having a hinged connection with the upper end of the post whereby the gate may swing about an upright axis into open or closed position, a track on the gate, an impact body movable along the track, interlocking means carried by said supporting element and the gate and including a latch engageable with the supporting element, when the gate is open, to latch the gate in open position, a releasing element pivotally mounted on the gate one end of which is associated with the track and whose other end is in alignment with the latch, said releasing element being normally inactive and being arranged to be actuated by said impact element, when the gate is open to move the releasing element into contact with the latch to release the same to permit the gate to close and means adapted to be contacted by the latch as the gate moves toward closed position to actuate the latch into contact with the releasing element, upon closing movement of the gate, to restore said releasing element to original, or inactive, position.

7. The combination with a gate post of a gate supporting element fixed relative to the lower end of the post, a gate pivotally supported on said element and having a hinged connection with the upper end of the post whereby the gate may swing about an upright axis into open or closed position, a track on the gate, an impact body movable along the track, interlocking means carried by said supporting element and the gate and including a latch engageable with the supporting

element, when the gate is open, to latch the gate in open position, a releasing element pivotally mounted on the gate one end of which is associated with the track and whose other end is in alignment with the latch, said releasing element being normally inactive and being arranged in the path of the impact element to be actuated by said impact element, when the gate is open to move the releasing element into contact with the latch to release the same to permit the gate to close, means arranged to be contacted by the latch to actuate the latch into contact with the releasing element, upon closing movement of the gate, to restore said releasing element to original, or inactive, position, said impact element being movable along the track to original, or inactive, position when the gate is closed.

8. The combination with a gate post, of a gate connected to the post to swing about an upright axis to open or closed position, means for automatically latching the gate open when the gate is moved to open position, said latching means comprising a ratchet element fixed in relation to the post and a latch on the gate arranged to cooperate with said ratchet element and means including a release element moveably supported on the gate and cooperable with said latch and a gravity actuated impact member movable along the gate, said release element being positioned in the path of said impact member and engageable by said member when said gate is opened to actuate said release element to release the latching means.

9. The combination with a gate post, of a gate connected to the post to swing about an upright axis to open or closed position, means for automatically latching the gate open when the gate is moved to open position, said latching means comprising a ratchet element fixed in relation to the post and a latch on the gate arranged to cooperate with said ratchet element, a release element pivoted on the gate and cooperable with said latch and an impact member mounted on the gate and movable by gravity, when the gate is open, said release element having a portion positioned in the path of said impact member and engageable by said member to actuate said release element to release said latch.

LYLE C. TILBURY.
